United States Patent Office.

GILES F. FILLEY, OF ST. LOUIS, MISSOURI.

Design No. 2,663, dated June 4, 1867.

DESIGN FOR A TRADE-MARK.

The Schedule referred to in these Letters Patent and making part of the same.

TO ALL WHOM IT MAY CONCERN:

Be it known that I, GILES F. FILLEY, of the city and county of St. Louis, in the State of Missouri, have originated and designed a new Design for a Trade-Mark, of which the following is a full, clear, and exact description, reference being had to the annexed drawing, making part of this specification.

My design consists of two oak leaves, one acorn, and one cup, arranged on a branch, substantially as shown in the accompanying drawing, in combination with the words "Charter Oak" and the rays, in the manner indicated by the drawing.

This design is intended to be affixed to my manufactured articles in the form of a casting in basso relieveo.

What I claim as my invention, and desire to secure by Letters Patent, is—

The design for a trade-mark, substantially as shown and described.

GILES F. FILLEY.
